[57] **CLAIM**

The ornamental design for an illuminated angled wire frame icicle display, as shown and described.

DESCRIPTION

FIG. 1 is a front elevational view of an illuminated angled wire frame icicle display showing my new design;

FIG. 2 is a right side elevation view thereof;

FIG. 3 is a left side elevational view thereof;

FIG. 4 is a top view thereof;

FIG. 5 is a bottom view thereof;

FIG. 6 is an enlarged view of one of the lights mounted on the wire frame as shown in circle 6 in FIG. 1, the display being fragmentarily shown for convenience of illustration; and,

FIG. 7 is a perspective view of the light and fragmentary frame of FIG. 6, the display being fragmentarily shown for convenience of illustration.
